(57) **CLAIM**

The ornamental design for a scraper for dishes, as shown and described.

DESCRIPTION

FIG. 1 is a top plan view of my design for a scraper for dishes;

FIG. 2 is a left side elevation view thereof, the opposite side being a mirror image thereof;

FIG. 3 is a front elevation view thereof;

FIG. 4 is a bottom plan view thereof;

FIG. 5 is a rear elevation view thereof;

FIG. 6 is a top plan view showing my design mounted on a trashcan; and,

FIG. 7 is a side elevation view showing my design mounted on the sidewall of a trashcan and a dish pulled upwardly against the scraper.

The broken lines in FIGS. 6 and 7 depict environment of the scraper for dishes and form no part of the claimed design.
